UNITED STATES PATENT OFFICE.

WILLIAM D. HAVILAND, OF LIMOGES, FRANCE, ASSIGNOR TO THEODORE HAVILAND & COMPANY, INCORPORATED, OF NEW YORK, N. Y., A CORPORATION OF NEW YORK.

DESIGN FOR A COVERED VEGETABLE DISH OR SIMILAR ARTICLE.

Application filed December 7, 1927. Serial No. 24,407. Term of patent 14 years.

To all whom it may concern:

Be it known that I, WILLIAM D. HAVILAND, a citizen of the United States, residing at Limoges, France, have invented a new, original, and ornamental Design for a Covered Vegetable Dish or Similar Article, of which the following is a specification, reference being had to the accompanying drawing, forming a part thereof.

The drawing shows in perspective a covered vegetable dish embodying my new design.

I claim:

The ornamental design for a covered vegetable dish or similar article as shown.

WILLIAM D. HAVILAND.
